C. R. WELCH

SAFETY DEVICE FOR HOISTS

Filed May 10, 1924

UNITED STATES PATENT OFFICE.

CLARENCE R. WELCH, OF DENVER, COLORADO.

SAFETY DEVICE FOR HOISTS.

Application filed May 10, 1924. Serial No. 712,497.

To all whom it may concern:

Be it known that I, CLARENCE R. WELCH, a citizen of the United States, residing at Denver, in the city and county of Denver and State of Colorado, have invented certain new and useful Improvements in Safety Devices for Hoists; and I do declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to safety devices for hoists, and has reference more particularly to a system adapted to be used in connection with mine hoists.

In mines and in other places where similar conditions prevail, material is hoisted from the mine to the surface. The hoist is operated either by steam or by electric energy. In either case the machinery is located at the surface and is under the control of an attendant. The hoist cage travels between an upper and a lower landing. As a rule it is loaded while at the bottom and unloaded at the top. There are several conditions essential to safety. First, the cage must be stopped at the proper position at both landings, second, the attendant must be prevented from starting the hoist before the cage is properly loaded and unloaded and, third, the engineer must not start the hoist in the wrong direction. In some places, automatic controllers are installed, which stop the machinery when the cage has reached the limit of travel in either direction, while in other places the entire responsibility rests upon the attendant or engineer.

In cases where automatic controllers are not employed, the engineer is governed in his actions by an indicator that shows the position of the cage at each instance. Such indicators are usually very simple and comprise a dial or a pointer that is rotated from the hoisting drum.

It is the object of this invention to produce a safety device which will automatically lock the controller lever in neutral position at the end of each travel of the hoist, as well as to put an obstruction in the

way of the reversing lever to prevent the latter from being moved in the wrong direction. Means is also provided whereby the loader at the bottom or the unloader at the top can release the controller and the reversing lever whenever the cage is ready to travel.

In order to explain my invention with the greatest degree of clearness, I shall have reference to the accompanying drawing in which the same is shown diagrammatically.

Numerical 1 designates a controller lever that is pivoted at 2 and has a rod 3 extending to the throttle valve of an engine or the controller of a motor as the case may be. Numerical 4 represents a reversing lever which, for the purpose of illustration, is shown pivoted at 5 and has attached to it a rod 6 that extends to and controls the reversing gear, if a steam engine is employed, or a reversing switch in case a motor is employed. Numerical 7 represents an indicator dial that is connected to the hoisting drum by means which cause it to rotate in unison therewith. The direction of rotation for the "up" and the "down" travel of the hoist is indicated by the arrows. The indicator dial is provided with holes 8 which serve to receive the pivot pins 9 of the pawls 10. A switch is located adjacent the dial 7 and is so constructed that it is operated by the pawls 10. In the present instance the switch is shown diagrammatically as consisting of a vertical member pivoted intermediate its ends at 11 and whose upper end 12 projects upwardly into the path of the pawls 10. Secured to the lower end 13 of the vertical member is a rod 14 which extends through the open center of the solenoid 15 and has attached to it two collars 16 and 17 which are spaced apart such a distance that the distances between their outer faces is equal to or slightly less than the length of the solenoid. Circular armatures 18 are slidably mounted on the rod 14 in the manner shown. The end of the rod is provided with a head 19.

It is now apparent that if the rod 14 is moved towards the right, the righthand armature will be moved to the dotted line position, and when the magnet is energized, the armature and rod will be returned to the full line position shown. If the rod 14 is moved towards the left, the lefthand armature will

be moved to the dotted line position and will, upon energization of the magnet, be returned to the full line position shown.

The control lever has a circular portion 20 concentric with the pivot 2 and this is provided with a notch 21. A solenoid 22 is located close to the lever. A rod 23 projects through the opening in the solenoid and has attached thereto an armature 24. A tension spring 25 has one end attached to the bracket 26 and the other end to the end of rod 23. This spring tends to move the armature away from the end of the magnet. The end of the rod 23 nearest the pivot 2 has a pawl 27 pivoted thereto at 28. A tension spring 291 imparts to the pawl a tendency to rotate about the pivot 28 in a counter-clockwise direction. When the magnet 22 is energized, the pawl 27 engages the edge of part 20 and when the controller handle moves to off position, it engages the notch 21 in the manner shown on the drawing and prevents the controller from being moved into running position while the solenoid 22 is energized.

On each side of the reversing lever 4, I have shown solenoid magnets 29 and 30. Each magnet has a cylindrical armature or core 31 whose axes coincide with the plane 30 of movement of the reversing lever. When the armatures are retracted in the manner shown in the drawing, the reversing lever can be moved freely from "up" to "down" position and back again. If, however, one of the magnets 29 or 30 are energized, the core will be projected towards the reversing handle and form a step which will act as a safety device to prevent the engineer from moving the lever to "up" position when the cages are at the top or to "down" position when the cage is at the bottom.

I will now explain the manner in which the various parts that I have described are interconnected and how they cooperate to produce the results desired.

The energy for operating the various magnets will be taken from the power supply available at the mines, but for the purpose of this explanation I have shown a battery 32. One pole of this battery is connected to the solenoid 22 by means of a wire 33. A second wire 34 extends from the other end of the solenoid coil to the terminals 35 and 35^a. From the other pole of the battery a wire 36 extends to the terminals 36 and 36^a. It is now apparent that when contact is made between either pair of contacts 35, 36 or 35^a, 36^a, the solenoid 22 will be energized and the armature 24 attracted and moved to the position shown in the drawing.

A wire 37 connects one end of the coils of each of magnets 29 and 30 with one pole of the battery 32. A wire 38 extends from this 65 same battery terminal to the contacts 39 and

39^a. A wire 40 connects the other end of the winding of magnet 30 with the terminal 43, while a wire 42 connects the magnet 29 in a similar manner with the contact 41. The switch member 12, 13 has secured thereto conducting portions 44 and 45 that are insulated from each other and adapted, respectively, to connect contacts 39, 43 or 39^a, 41 and contacts 35, 36 or 35^a—36^a when the switch occupies one or the other of the 75 dotted line positions.

Let us now assume that the hoist is traveling upwardly. The controller lever 1 will occupy the running position; the reverse lever 4 will be in the "up" position, and the 80 indicator disk will rotate in the direction of the arrow marked "up". When the engineer sees that the hoist is near its upper limit of travel he brings the controller handle to off position. A short time before the hoist reaches the end of its travel, one of the lugs 10 will engage the arm 12 and rotate the switch member counter-clockwise into dotted line position. This energizes the magnets 22 and 29. The rod 23 is projected to the left into the position shown and at the same time the core armature 31 of magnet 29 is moved towards the lever 4. Since the arm 12 of the switch moves about the pivot 11, its end travels in the arc of a circle, and since the pawls 10 also travel in a circular path which intersects the path of the end of arm 12, it is evident that by properly spacing the parts, the pawls 10 will be permitted to move the switch to closing position and then pass by the end of arm 12 so that the latter will be free to be moved back to neutral position. It is for this purpose that the pawls 10 are pivoted at 9. When the cage has been unloaded, the switch S¹ is 105 closed. This energizes the solenoid 15 and brings the switch back to neutral position. This releases the controller handle and permits the engineer to start the hoist. The magnets 29 and 30 must, of course, be made 110 of sufficient strength to move the reversing lever to neutral position whenever either magnet 29 or 30 is energized. When the hoist cage approaches the lower level, the other pawl 10 throws the switch member in 115 the opposite direction, thereby energizing magnets 22 and 30. When the cage is ready for the return trip, the switch 52 is closed. This releases the control and reverse levers in the manner explained.

From the above, it will be apparent that I have devised a combination of elements operatively related to each other and cooperating to produce a safety device that will reduce to a minimum accidents due to the premature starting of hoists. As explained above, the control lever is automatically locked in off position when the hoist reaches the end of its travel in either direction. The reversing lever is automatically returned to 120 125 130

neutral position at the ends of the hoist travel and the hoist is thereby held against accidental stopping. Switches are provided at the top and bottom for releasing the locking means when the hoist cage is in condition to be moved.

Having now described my invention, what I claim as new is:

1. A hoist safety system comprising, in combination, a controller lever, an indicator adapted to move at a speed proportional to the speed of a hoist cage, an electromagnetic device operatively related to the control lever and adapted to lock the same in "off" position, means operated by the indicator for causing said electromagnetic device to function when the indicator passes a predetermined point, and manually operated means for restoring said device to normal position.

2. A safety system for hoist control, comprising, in combination, an indicator adapted to move at a rate proportional to the rate of a hoist cage, a switch located adjacent the indicator, means on the indicator for moving said switch in one direction when the indicator passes a predetermined point in one direction, means on the indicator for moving said switch in the opposite direction when the indicator passes a predetermined point while moving in the other direction, a controller handle for stopping and starting said indicator, an electromagnetic device operatively related to the controller, said device being adapted when energized to lock the controller in off position, and means controlled by the switch for rendering said device operative or inoperative.

3. A safety system for hoist control, comprising, in combination, an indicator adapted to move at a rate proportional to the rate of a hoist cage, a switch located adjacent the indicator, means on the indicator for moving said switch in one direction when the indicator passes a predetermined point in one direction, means on the indicator for moving said switch in the opposite direction when the indicator passes a predetermined point while moving in the other direction, a controller handle for stopping and starting said indicator, an electromagnetic device operatively related to the controller, said device being adapted when energized to lock the controller in off position, and means controlled by the switch for rendering said device operative or inoperative, a reversing lever, and electromagnetic means operatively

related to the lever and to the switch for moving said lever to neutral position when the switch operates.

4. A safety system for hoist control, comprising, in combination, an indicator adapted to move at a rate proportional to the rate of a hoist cage, a switch located adjacent the indicator, means on the indicator for moving said switch in one direction when the indicator passes a predetermined point in one direction, means on the indicator for moving said switch in the opposite direction when the indicator passes a predetermined point while moving in the other direction, a controller handle for stopping and starting said indicator, an electromagnetic device operatively related to the controller, said device being adapted when energized to lock the controller in off position, means controlled by the switch for rendering said device operative or inoperative, a reversing lever, electromagnetic means operatively related to the lever and to the switch for moving said lever to neutral position when the switch operates, and electromagnetic means connected to the switch and adapted to move the same into inoperative position.

5. A safety system for hoist control, comprising, in combination, an indicator adapted to move at a rate proportional to the rate of a hoist cage, a switch located adjacent the indicator, means on the indicator for moving said switch in one direction when the indicator passes a predetermined point in one direction, means on the indicator for moving said switch in the opposite direction when the indicator passes a predetermined point while moving in the other direction, a controller handle for stopping and starting said indicator, an electromagnetic device operatively related to the controller, said device being adapted when energized to lock the controller in off position, means controlled by the switch for rendering said device operative or inoperative, a reversing lever, electromagnetic means operatively related to the lever and to the switch for moving said lever to neutral position when the switch operates, and electromagnetic means connected to the switch and adapted to move the same into inoperative position, and means for controlling said last-named means, said means comprising switches located at convenient points.

In testimony whereof I affix my signature.

CLARENCE R. WELCH.
